CLAIM

The ornamental design for a automated cash system cassomat A.C.S., as shown and described.

DESCRIPTION

FIG. 1 is a front perspective view of an automated cash system cassomat A.C.S. showing our new design;
FIG. 2 is a right side elevational view thereof;
FIG. 3 is a left side elevational view thereof;
FIG. 4 is a top plan view thereof;
FIG. 5 is a bottom plan view thereof;
FIG. 6 is a front elevational view thereof;
FIG. 7 is a rear elevational view thereof;
FIG. 8 is a front perspective view of a second embodiment of an automated cash system cassomat A.C.S. showing our new design;
FIG. 9 is a right side elevational view thereof;
FIG. 10 is a left side elevational view thereof;
FIG. 11 is a top plan view thereof;
FIG. 12 is a bottom plan view thereof;
FIG. 13 is a front elevational view thereof; and,
FIG. 14 is a rear elevational view thereof.
